(57) **CLAIM**

The ornamental design for "ceiling light," as shown and described.

DESCRIPTION

FIG. 1 is a lower front perspective view of a ceiling light in accordance with our new design;

FIG. 2 is a front elevation view thereof, the rear elevation view and side elevation views being identical thereto;

FIG. 3 is a top plan view thereof; and,

FIG. 4 is a bottom plan view thereof.

The subject matter shown in broken lines in FIG. 3 forms no part of the claimed design.
